GB 2 172 198 A 9/1986

Primary Examiner—Janice E. Seeger

(74) *Attorney, Agent, or Firm*—Fish & Neave IP Group, Ropes & Gray, LLP

(57) **CLAIM**

The ornamental design for a drawer for a plastic mattress foundation drawer, as shown and described.

DESCRIPTION

FIG. 1 is a perspective view of a plastic mattress foundation drawer, showing my new design; and,

FIG. 2 is a front perspective view, showing the design in an alternate environment.

The phantom lines depicting a mattress, portions of a mattress foundation, and portions of a drawer are for illustrative purposes only and form no part of the claimed design.
